BOILER STRUCTURE

John J. Oakes, Chinchilla, Pa.

Application February 14, 1947, Serial No. 728,580

6 Claims. (Cl. 122—288)

1

This invention relates to a boiler structure, and more particularly concerns the assembly and arrangement of tubes affording baffled flue passages and provided by multiple units which can be made, assembled and replaced.

A feature of the invention is the construction of a unit for such a boiler from lengths of tubing which are joined by welding or like joints to form an integral piece.

Another feature is the construction of a unit for such a boiler from lengths of tubing of different diameters whereby the parts of larger diameter provide closing walls around flue spaces when the units are joined, while the parts of smaller diameter provide heating elements interposed in the flue spaces.

Another feature is the construction of such units of lengths of tubing which are smooth internally and so disposed that the major heating elements provide free flow and downward passage for mud and sludge.

A further feature is the provision of a boiler structure comprised of multiple units each having side members, and a top member formed of lengths of tubing joined together, and wherein certain units also have a cross member connecting the side members below the top, and certain units have a vertical tube connecting such a cross member with the top, whereby to provide a furnace arch and a flue space thereover which is divided by a baffle or partition formed by said vertical tubes.

With these features as objects in view, an illustrative practice of the invention is shown in the accompanying drawings, in which:

Figure 1 is a perspective view of the boiler structure with the surrounding housing, lagging and attached parts;

Figure 2 is a corresponding perspective view with the housing, lagging and attached parts omitted;

Figure 3 is an upright sectional view through the structure of Figure 1, essentially representing the same with the front plate and the front parts of the lagging removed, and the other parts of the side wall and top wall lagging broken away to show header connections;

Figure 4 is an end elevation of a front unit;

Figure 5 is an end elevation of a first central unit;

Figure 6 is an end elevation of a second central unit;

Figure 7 is an end elevation of a rear unit;

Figure 8 is a horizontal section through the

2

flue space of the illustrated structure, substantially on the lines 8—8 of Figures 3 to 6.

In these drawings, the boiler has an enclosing jacket or housing H, which includes the front plate J having the fire box door K, the ash pit door A, and the flue clean-out doors L, and a rear plate M having an outlet for the chimney pipe N. The plates J, M are connected by tie bolts R passing through eyes formed on the plates. Within this jacket is a fireproof and heat-insulating lagging P. The illustrated boiler is for hot water house-heating service, and has the hot-water delivery pipe S and the water returns T.

The boiler is formed of multiple units A, B, C, and D, and the headers E and F. Each of the multiple units is formed of water tubes and is constructed by cutting metal tubing to size and shape, and joining the parts by welding. Each

20 of the units has the upright side members 10, 11 and the top member 12. The lower ends of the side members are closed by plates 13, and are provided with the downwardly and outwardly directed connection pipes 14 of small diameter and of a length to extend through the lagging P.

The front unit A has a cross tube 15 connecting the side members 10, 11 at an intermediate level of their height; this cross tube illustratively being formed to slope upwardly toward its center at angles of about five degrees to the horizontal. The unit A also has a central upright tube 16 which joins the top member 12 to the header E. Smaller upright tubes 17 also connect the cross tube 15 and top member 12, at points spaced from the centers thereof.

The central units B and C likewise each have the side members 10, 11; the top member 12; the plates 13 with connection pipes 14; the intermediate level tube 15; the top connection 16; and the small upright water tubes 17. The units B and C also have the upright central tubes 18 which join the center of the tube 15 with the center of the top member 12 in each unit. The units B and C differ from one another, when viewed from the front of the assembly, in that the tubes 17 are staggered relatively to right and left (Fig. 8).

The rear unit D has the side members 10, 11; the top member 12; the plates 13 with connection pipes 14; the top connection 16; and the central upright tube 18. In this unit D, the intermediate level tube 15A only extends from side member 10 to the upright central tube 18, and the smaller upright tubes 17 are provided at this side only.

These units are identical in external outline and shaped so that they can be arranged close together, wherewith the side member 10 of each central unit abuts the side members 10 of the adjacent units for its entire height to provide a side wall for the furnace and flue spaces. Likewise the side members 11 provide a side wall, and the top members 12 provide a top wall. The tubes 15 likewise abut and provide an arch over the furnace or fire box space, which is closed at the front and sides, but has an opening at the right rear, in the illustrated form, due to the omission of one-half of the intermediate level tube in providing the member 15A (Fig. 7). The upright tubes 18 also abut one another, and provide a baffle wall which divides the flue space above the arch wall formed by tubes 15, 15A; the omission of the tube 18 from the front unit A (Figs. 3 and 4) provides a connecting opening through this baffle wall.

The small tubes 17 in the central units B and C are staggered with relation to one another (Figs. 4, 5 and 8), so that large areas are presented to the hot gases passing forwardly in the right-hand part of the flue and rearwardly in the left-hand part thereof as indicated by the arrows and these gases are deflected and their heat content caused to transfer to the several tubes 10, 11, 12, 15, 17, 18, and thus to the fluid in these tubes.

In erecting the furnace, a desired number of the central units B and C are positioned in alignment and against one another, and the front and rear units A and D positioned to complete the nest. Headers E, F of the proper length and having pipe connection stubs of the proper size and spacing are placed opposite the pipes 14, 16, and connected thereto by the separable unions shown. The lagging is placed, and the jacket installed, the tie bolts R being drawn tight before the luting or lagging material sets.

In use as a hot water boiler, the water returns to the lower manifolds or headers F, and passes through the pipes 14 to the respective units. The water flows in the pipes 10, 11 and 15 which are of larger size, and through the pipes 17 of smaller size, at rates dependent upon the thermal change of density produced by the heating of these pipes. The heated water then enters the top-tube member 12 and passes through top connection 16 to the top manifold or header E, and thence is delivered for service in the usual way.

In use as a steam boiler, the water supply by return or feeding system is brought into the lower headers F to establish a desired level in the system, preferably above the tubes 15 providing the fire arch, and usually to a level close to the upper tubes 12 or even above the lower inner surfaces of these tubes, but below the upper inner surfaces of these tubes. The water is heated and steam generated in the tubes, and collects in the tubes 12 and thus passes to the upper or outlet header E.

The furnace space below the arch formed of pipes 15 is illustrated (Fig. 3) as including a grate W on which is a bed of coals Y, from which the hot gases rise and flow rearward, with the lower surfaces of tubes 15 and the inner surfaces of the lower ends of side members 10, 11 being heated from the coals and the gases by radiation and convection. The gases then pass upwardly at the right rear, between tubes 11 and 18 of unit D, and move forwardly through the right-hand flue space, therewith heating the tubes 17, the inner surface of the upper part of tubes 11, the lower

surface of top members 12, and the right-hand surfaces of tubes 18. The gases then pass across the front of the tube 18 of the first unit B, through the space provided by omitting tube 18 from the unit A; and thence rearwardly in the left-hand flue space, heating the exposed tube walls. The gases then pass through the smoke pipe N to the stack.

The boiler can be assembled for the desired capacity by employing one each of the front and rear units A, D, and the desired number of central units B, C, to provide the intended heating area. The lengths of the headers E, F, the side parts of the jacket, and the tie bolts R are correspondingly selected.

In the illustrated form, the tubes 14, 16 are provided at their ends with union couplings located outside the lagging P, for connection to the mating flanges provided on the headers E, F. In this way, if any individual unit fails by burning out, plugging, or other damage, the tie bolts, jacket and lagging can be removed, the connected couplings of the unit separated, and the unit withdrawn and replaced by another. Also, it is feasible to operate the boiler upon failure of a unit and while awaiting a new unit, by separating the couplings of the defective section, and placing caps upon the header stub tubes.

In practice, a boiler of this type formed of fourteen units having the larger tubes 10, 11, 13, 15, 18 of four-inch tubing, and the smaller tubes 17 of two-inch tubing, can furnish hot water for up to 4,000 square feet of radiation, amounting to about 35 feet of radiation for each square foot of heating surface and an evaporation rate of about 14½ pounds of water per pound of coal.

It is obvious that the illustrated form is not restrictive, and that the invention can be used in many ways within the scope of the appended claims.

I claim:

1. A boiler comprising a plurality of units, each unit being composed of tubes cut and welded together to provide upright side members, a top member, and an intermediate cross member at a level between the upper and lower ends of the side members, said units including central units each having also a vertical tube connecting the top and cross members thereof, said units also including a front unit from which such a vertical tube is omitted, and a rear unit having its cross member extending only from one side member to the vertical tube, the latter providing a passage for movement of furnace gases from below the level of the cross members into the flue space above the same, said members and vertical tubes having essentially identical dimensions from front to back of the respective unit, said units being assembled with said side and top members forming walls above the cross members to provide the said flue space, and said vertical tubes mutually abutting to constitute a partition wall dividing said flue space, and means effective to hold the units assembled.

2. A boiler as in claim 1, in which the units also have tubes smaller than said members and connecting said top and cross members thereof.

3. A boiler as in claim 2, in which the smaller tubes in successive members are staggered relative to one another for providing tortuous paths to the gases moving in the flue space.

4. A boiler as in claim 1, in which each unit has connection pipes extending downward and outward from the bottoms of the side members and also has connection pipes extending upward

from the top member, inlet and outlet headers having connection pieces alined with said pipes, and separable pipe connections joining each said pipe with its corresponding connection piece.

5. A boiler comprising a plurality of units of identical outer size and shape, each unit being composed of upright side members connected by a top member, one end unit and the central units having also a cross member at a level between the upper and lower ends of the side members and connecting said members, the other end unit having a cross member at said level and connected to one side member and terminating short of the other side member, the central units and said other end unit each having a vertical tube connecting the cross member with the top member, said units being assembled with said side and top members forming essentially closed walls and said cross members abutting and forming a fire arch wall essentially closed except for the space where 10 15 20 the cross member of the said other end unit ter-

minates short of a side member, and with the vertical tubes forming an essentially closed wall extending along the boiler except above the cross member of said one unit, and means effective to hold the units assembled.

6. A boiler as in claim 5, in which the cross members are inclined upwardly and away from the respective connected side members at substantially five degrees to the horizontal.
